UNITED STATES PATENT OFFICE.

ELLA A. BENNETT, OF DEXTER, IOWA.

DRESSMAKING SYSTEM.

1,183,845.

Specification of Letters Patent. Patented May 23, 1916.

Application filed July 9, 1914. Serial No. 850,038.

To all whom it may concern:

Be it known that I, ELLA A. BENNETT, a citizen of the United States, and resident of Dexter, in the county of Dallas and State 5 of Iowa, have invented a new and useful Dressmaking System, of which the following is a specification.

My invention relates to improvements in dressmaking systems so that any woman, 10 without special instructions in dressmaking, can cut and fit ladies' and children's garments, and at the same time insure a perfect fit.

My object is to provide improvements in 15 dressmaking systems requiring but simple and inexpensive apparatus for cutting and fitting the garment. I attain this object by the devices illustrated in the accompanying drawings, in which:

20 Figure 1 shows one of the pattern strips of material, as used in my system, with a front waist pattern drawn thereon. Fig. 2 shows a similar strip of material with a backwaist pattern drawn thereon, and Fig. 25 3 shows another somewhat similar strip of material, showing the method of cutting a sleeve of a garment by my system.

I have illustrated my method of cutting 30 three patterns for a waist, namely the front, back and sleeve patterns, the method of cutting the sleeve pattern being the one which more fully illustrates the method and devices upon which I wish to obtain a patent. It is also to be understood that my method 35 is not to be limited to the three patterns illustrated but may be applied to any patterns that may come within the scope of my invention.

When it is desired to cut the three patterns for a waist, as just described, I first provide three strips of paper or any other similar material, one for the front, about twenty inches wide and twenty-five inches long, provided with a horizontal line 10—11 45 about four inches from the top and extending from the center to the right hand edge of the paper (Fig. 1). I provide another strip for the back pattern, twenty inches wide and twenty-one inches long, with a horizontal line 12—13, extending from the center to the left hand edge and about six inches from the top (Fig. 2). I provide a third strip from which a sleeve pattern is to be cut, about twenty inches wide and 50 twenty-eight inches long, and provided with a vertical, central line 14—15, and a hori-

zontal line 16—17, about eight inches from the top edge of said strip.

Before attempting to draw the pattern on the sheets that I have provided, I measure a horizontal line across the chest, at the junction of the neck of the person, to whom the garment is to be fitted from outside shoulder point to outside shoulder point, and then measure one down the center front 60 from the junction of the neck to the waist line, then one down the center of the shoulder and one from directly under the arm to the waist line and one down the center of the back and one straight across the back, 65 approximately four inches below the neck. I also measure a horizontal line around the arm at the point where the lowest part of a sleeve joins the body of a waist. All measurements must be taken just as the garment 70 is wanted to fit. If some parts are wanted loose and others tight, the measurements must be taken that way.

To draw a diagram of the front waist pattern, I take on the line 10—11 a distance 80 equal to one-half of the line drawn across the chest at the junction of the neck. It will thus be seen that I have formed on the strip of paper indicated in Fig. 1 a foundation, which corresponds to the line drawn 85 across the chest of the wearer to whom the garment is to be fitted. It will be seen that other measurements may be transferred from the wearer to the pattern, using the said line as a foundation. The right hand 90 edge of the strip of paper from which the pattern is to be cut serves as a second foundation line, from which measurements may be taken, and corresponds to the line which is drawn down the center front from 95 the junction of the neck to the waist line. A point is taken above the line 10—11 at 40, which point is spaced from the right hand edge of the paper in Fig. 1 a distance equal to half the circumference of 100 the neck at the junction with the head. The point 40 is spaced above the line 10—11 equal to the distance from the line drawn across the chest to the line drawn down the center shoulder. A curved line is then 105 drawn from the point 40 downwardly toward the line 10—11 and laterally toward the righthand edge of the paper. A point 41 is marked on the paper above the line 10—11 to the left of the point 40 a distance 110 equal to the distance from the neck to the point of the shoulder. The point 41 is

spaced above the line 10—11 a distance equal to the distance from the line drawn across the chest upwardly to the point of the shoulder. The difference in the distance from 5 the point 41 to the line 10—11 and the distance from the point 40 to the line 10—11 is the shoulder drop. A point 42 is marked on the paper below and to the left of the line 10—11 at a distance from the righthand 10 edge of the paper equal to the distance between the line drawn down the center front of the person to be fitted to the upper end of the line under the arm.

The armseye is determined by the distance 15 from the line drawn across the chest to the last described line. A line is drawn from the point 42 almost substantially horizontally toward the righthand edge of the paper a distance equal to half the distance 20 from the point 42 to a line spaced vertically downwardly from the point 10, or about two inches, and the line is then curved upwardly to the point 10. A point 43 is marked at the righthand edge of the paper 25 at a distance below the line 10—11 equal to the distance from the line drawn across the chest to the waist line in front. A point 44 is marked on the paper spaced from the right-hand edge thereof, a distance equal to the 30 distance from the center front along the waist line, to a line drawn downwardly underneath the arm, plus about four inches for fullness. The amount allowed for fullness may be varied as may be desired. 35 The point 44 is located below the point 42 a distance equal to the length of the line drawn from under the arm to the waist line. A line is drawn from the point 42 to the point 44 and from the point 44 to the point 40 43. The last described line may be curved 45 downwardly somewhat as desired.

The pattern for the back of the waist is obtained in a similar manner and there is measured on the line 12—13, beginning at 45 the lefthand edge of the sheet, a distance equal to one-half the length of the line drawn straight across the back about four inches below the neck, and the left hand edge of the sheet of paper in Fig. 2 corresponds to the line drawn down the center of the back. For the purposes of the illustration, it is assumed that the measurement just made is equal to the length of the line 12—13.

On Fig. 2 I have indicated the lower end 55 of the line from the arm pit to the waist at 45, and have indicated the point directly under the arm 46. A line is drawn between the points 45 and 46, and a horizontal line is drawn from the point 45 to the left edge 60 of the paper at 47. The part of the pattern at the point of the shoulder at the neck is indicated at 48. The outer point of the shoulder is indicated at 49. The upper part of the center of the back of the neck is indicated at 50.

For drawing the sleeve pattern I have used a strip of paper similar to that illustrated in Fig. 3, having a vertical line 14—15 and a horizontal line 16—17 thereon. I mark on the line 16—17 points 16 and 17, 70 at equal distances from the line 14—15, having a space between them equal to the circumference of the sleeve, taken at a point where the sleeve and the waist join. I then mark on the line 14—15 a point at 18. The distance from the point 18 to the line 16—17 is equal to the distance taken from a point on the outside of the arm in the line which was drawn circumferentially around the arm to a point on the shoulder where the sleeve and 80 waist thereto join. The front and back patterns are then cut from the paper according to the outlines as shown by the dotted lines in Figs. 1 and 2. To form the top of the sleeve pattern I pin the front and back patterns together at under arm, with the front pattern at the right with its righthand edge parallel with the righthand edge of the sleeve pattern sheet. The front and back pattern are so placed on the sleeve pattern sheet that the lower end of the curved part of the line 10—42 is at the point 17 with the line 41—40 extending substantially horizontally toward the righthand edge of the sleeve pattern sheet, and the point 46 on the back pattern is adjacent to the point 42, while the line or edge 46—45 is along the line or edge 42—44. A line is then drawn from the point 17 to the sleeve pattern sheet, or a point corresponding with the point 42 on the front pattern and is continued along the line 46—13 to a point at 24. The point at 24 is located above the line 16—17 a distance equal to one-half the distance from the point 46 to the point 49. A curved line 105 is then drawn upwardly and inwardly to the point 18. I then unpin the waist pattern and place the front pattern with the lower part of the curved part of the line 10—46 over the point 16 of the line 16—17 and position the pattern so that the lower right hand corner will be approximately two inches from the line 14—15. I then draw a line on the sleeve pattern sheet from the point 16 upwardly following the outline of the 115 line 10—42 to a point 29, which is located above the line 16—17, the same distance as the point 24 and then remove the front and back pattern and draw a curved line from the point 29 to the point 18, a horizontal line 30 is drawn below the line 16—17 and the line 30 is spaced from the line 16—17 a distance equal to the distance from the line drawn around the arm to the hand. The length of the line 30 is determined by measuring loosely around the hand. The lines 31 and 32 are drawn from the points 16 and 17 to the ends of the line 30. Half the hand measure plus one inch is placed on the left-hand side of the line 18—15, and half the 120 125 130

distance less one inch is placed on the right-hand side, as shown in Fig. 3. This gives me the outline for the upper portion of the sleeve pattern and when drawn as I have 5 described and illustrated the pattern may then be cut out and the parts placed together in their proper relation to each other and a perfect fit will thus be obtained.

It is to be understood that the lines 30, 31 10 and 32 of the sleeve pattern are found in the usual way.

Thus it will be seen that I have obtained a very simple, practical and inexpensive 15 method of cutting garments, which can be readily understood by the average person.

What I claim is:

1. In a device of the class described, the 20 method of laying out patterns comprising the superposing upon a strip of flexible material, having a vertical, central foundation line and a second line drawn transversely thereto, near the top of said strip, of a front and a back pattern secured together and superposed on said strip with certain 25 predetermined points in said patterns over certain predetermined points in certain portions of said lines ascertained by measure-

ment of the person fitted, said front and back patterns when thus superposed forming an outline from which certain portions 30 of a third may be taken.

2. In a device of the class described, the method of laying out a pattern comprising the superposing on a strip of flexible material having a vertical central foundation 35 line and a second line drawn transversely thereto, near the top of said strip, of a front and a back pattern secured together and superposed on said strip, with certain predetermined points in said patterns over 40 certain predetermined points in said lines ascertained by measurement of the person to be fitted, certain portions of said front and back patterns when thus superposed forming a pattern by which certain portions of a 45 third may be taken, the similar parts of said patterns thus formed being designed to coincide with each other when placed together in a garment.

Des Moines, Iowa, June 19, 1914.
